UNITED STATES PATENT OFFICE.

ATHERTON D. CONVERSE, OF WINCHENDON, MASSACHUSETTS.

TOOL-BOX.

1,175,127.

Specification of Letters Patent. Patented Mar. 14, 1916.

Application filed February 12, 1915. Serial No. 8,390.

To all whom it may concern:

Be it known that I, ATHERTON D. CONVERSE, a citizen of the United States of America, and a resident of Winchendon, in the county of Worcester and State of Massachusetts, have invented certain new and useful Improvements in Tool-Boxes, of which the following is a specification.

This invention relates to boxes and particularly to boxes the top and side faces of which are formed of wooden panels protected by metal plates.

The invention has for its object the provision of a box of this class in which the material used therein will be free to shrink and swell without affecting the surface of the box.

The invention consists of securing the metal plates to the top and side panels of the box by a single securing device positioned centrally in each metal plate, the edges of the latter being inclosed in grooves formed in strips or moldings surrounding the box while interposed between the top and bottom strips are metal corner pieces overlapping the ends of the metal plates secured to the sides of the box.

The invention further consists of certain novel features of construction and arrangement of parts which will be fully understood by reference to the description of the drawings and to the claims hereinafter given.

Of the drawings: Figure 1 represents a perspective of a box embodying the principles of the present invention. Fig. 2 represents a longitudinal section through the top or cover of the box. Fig. 3 represents a horizontal section through one corner of the top of the box. Fig. 4 represents a horizontal section of one corner of the box, the cutting plane being on line 4-4 on Fig. 1, and Fig. 5 represents a vertical section of one corner of the box, the cutting plane being on line 5-5 on Fig. 1.

Similar characters designate like parts throughout the several figures of the drawings.

In the drawings, the box therein shown is provided with side panels 10 and a top panel 11, preferably formed of wood. The edges of the panel 11 are inclosed in grooves 12 in the strips or moldings 13 surrounding the edge of said panel. The strips or moldings 13 are also provided with grooves 14

of greater depth than the depth of the grooves 12, these grooves 14 being adapted to receive the edges of the metal plate 15 secured to said panel 11 at one point only, the single securing device 16 being positioned adjacent the center of said plate so that the expansion and contraction of the metal plate will be equal in all directions, and will not affect the panel to which it is secured as would be true if the metal plate was secured to the panel at various points. The groove 14 is of sufficient depth to permit the plate to expand and contract without uncovering the edge thereof.

Heretofore where metal plates have been secured to the panels several securing devices have been used positioned at different points, and when expansion and contraction of the dissimilar materials take place, a buckling occurs that materially disfigures the appearance of the box.

The top of the box proper is surrounded by the strips 17, while its bottom is surrounded by the strips 18 to which is secured the bottom 19. At each corner of the box is positioned a metal corner member 20 the ends of which are set into the top and bottom strips 17 and 18 respectively as indicated in dotted lines in Fig. 5 of the drawings. The side panels 10 have each secured to the outer face thereof metal plates 21, the ends of which extend beyond the edges of said corner pieces 20 which overlap said ends at all times during the expansion and contraction thereof, which occur equally in all directions from the central securing device 22. The upper edges of the plates 21 are positioned in grooves 14 in the strips 17, while the lower edges are positioned in similar grooves 14 in the strips 18. By thus securing each metal plate 15 or 21 by a single centrally positioned securing member, the material of the box is free to expand and contract at will without injuring or disfiguring the box.

It is believed that the many advantages of this invention will be fully understood from the foregoing description.

Having thus described my invention, I claim:

1. In a device of the class described, a box having wooden top and side panels; a metal plate secured to the outer face of one of said panels at a single point adjacent the center thereof; and strips surrounding the

edge of said plate having a groove therein to receive the edge thereof.

2. In a device of the class described, a box having wooden top and side panels; a metal plate secured to the outer face of one of said panels at a single point adjacent the center thereof; and strips surrounding the edge of said plate having two grooves therein one to receive the edge of a panel and the other to receive the edge of the metal plate secured to said panel.

3. In a device of the class described, a box having wooden top and side panels; a metal plate secured to the outer face of one of said panels at a single point adjacent the center thereof; and strips surrounding the edge of said plate having two grooves therein, one to receive the edge of a panel and the other having a greater depth to receive the edge of the metal plate secured to said panel.

4. In a device of the class described, a box having its top and sides formed of wooden panels; a metal plate secured at its center only to each of said panels; strips at the top and bottom of said box having grooves therein to receive the top and bottom edges of said panels and metal plates; and metal corner pieces interposed between said top and bottom strips and secured thereto with

their edges overlapping the ends of said metal plates.

5. In a device of the class described, a box having its top and sides formed of wooden panels; a metal plate secured at its center only to each of said panels; strips at the top and bottom of said box having grooves of different depths therein to receive the top and bottom edges of said panels and metal plates; and metal corner pieces interposed between said top and bottom strips and secured thereto with their edges overlapping the ends of said metal plates.

6. In a device of the class described, a box having wooden top and side panels; a metal plate covering a panel with its edges extending beyond the edges of said panel; and strips secured to said panel and surrounding the edges thereof having grooves therein to receive the edges of said plate, the bottoms of said grooves being outside the edges of said plate under normal conditions.

Signed by me at 4 Post Office Sq., Boston, Mass., this 11th day of February, 1915.

ATHERTON D. CONVERSE.
